UNITED STATES PATENT OFFICE.

JAMES C. ANDERSON, OF HIGHLAND PARK, ILLINOIS.

CLAY BLOCK FOR PAVING, &c.

SPECIFICATION forming part of Letters Patent No. 379,926, dated March 27, 1888.

Application filed August 6, 1887. Serial No. 246,311. (No model.)

To all whom it may concern:

Be it known that I, JAMES C. ANDERSON, a citizen of the United States of America, residing at Highland Park, in the county of Lake 5 and State of Illinois, have invented certain new and useful Improvements in Clay Blocks or Bricks for Paving and other Purposes, of which the following is a specification, reference being had therein to the accompanying 10 drawings.

My invention relates to improvements in blocks or bricks for paving and other purposes.

The object of my invention is to produce a block or brick for paving purposes from clay, 15 which will be solid throughout, free from warpage, and not liable to be broken by heavy traffic or travel thereon.

My invention consists in making bricks or blocks for paving and other purposes of any 20 desired size from a series of thin or comparatively thin slabs made from dry clay powder under great pressure and uniting or joining these slabs or sections with a vitrifiable material to form the bricks or blocks.

25 It is well known that dry clay cannot be compressed in large bodies or quantities to a great degree of density, but when pressed in small quantities into thin or comparatively thin blocks or slabs an exceedingly high degree of density and strength is imparted to them, so that the article when properly burned 30 is not liable to be affected by abrasion, is not easily broken, and, owing to non-absorptive qualities of moisture, remains practically unaffected by the frost.

Bricks or blocks for paving purposes, as heretofore made from clay, have been either 35 so porous as to absorb a large percentage of water, thus causing the granules of clay to rapidly separate or disintegrate under the travel of vehicles or the action of the frost, or else they have been vitrified by intense heat, so that the surface of the roadway will be so slippery as to endanger life and limb.

40 Referring to the drawings, Figure 1 is a view in perspective of a block or brick for paving and other purposes. Fig. 2 is a sectional view of the block shown in Fig. 1. Fig. 3 is a perspective view of a hollow block made in accordance with 45 this invention. Fig. 4 is a sectional view of a paving-block in which the slabs or sections

composing the same are beveled at their upper edges, so as to form a roughened or uneven surface to prevent horses from slipping. Fig. 5 is a top or plan view of several of the blocks 55 shown in Fig. 4 as laid in the roadway.

A indicates a block or brick for paving or other purposes, made up of a series of thin slabs or blocks, a, said slabs being made of dry pulverized clay, under great pressure, 60 which thoroughly compacts or solidifies the clay, so that the size and number of the pores are reduced to the minimum and the strength of the blocks increased as against the ordinary way of molding blocks from damp or wet clay. 65

The blocks A may be made of any desired size or configuration, and, as before stated, are composed of a series of slabs or blocks, a, secured together by any suitable vitreous material which will fuse in the burning, thus causing 70 the slabs to unite firmly together and form the solid block A.

The blocks A may be formed prior to or at the time they are set in the kiln. The only precaution necessary is to place the desired number 75 of small slabs or blocks together with the vitrifiable material c between them, and then subject them to a vitrifying or burning heat, which not only burns the block to the desired hardness, but also fuses the material used in cementing the blocks or slabs together.

The blocks A may be provided with conical holes formed in the sides thereof for holding hydraulic or other cement, which holds or maintains the blocks in position on the road- 85 bed, as shown and described in Patent No. 220,693, granted myself and J. Greenawalt, October 21, 1879.

In Fig. 3 I have shown a hollow block made up of a series of small slabs a. This form of 90 block may be used to advantage in certain locations, and under certain circumstances is much more readily handled and is more easily burned.

In Figs. 4 and 5 I have shown the tops of 95 the sections a beveled off at b, which when placed together in the block form gutters or depressions, and when these blocks are laid as indicated in Fig. 5—i. e., with the small grooves running in the direction of the roadway and transversely thereto, alternately—it will form a sure and safe surface and thus pre-

vent the animals from slipping or falling. Both edges of the slab may be beveled, as shown in Fig. 4, so that the blocks can be reversed if found necessary.

5 A brick or block formed in the manner above indicated will be found to be very dense and hard and will not absorb moisture.

Having thus described my invention, what I claim, and desire to secure by Letters Patent, to is—

1. A block for paving and other purposes, composed of a series of clay slabs or blocks, such as described, joined together by a vitreous or vitrifiable material, as set forth.

2. A block for paving and other purposes, 15 composed of a series of clay slabs or blocks joined together by a vitreous material, said slabs being beveled at their edges to form grooves or depressions, as set forth.

In testimony whereof I affix my signature in 20 presence of two witnesses.

J. C. ANDERSON.
